CLAIM

The ornamental design for a label sheet with a feed edge assembly, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a first embodiment of a label sheet with a feed edge assembly showing our new design; FIG. 2 is a front view of a second embodiment of a label sheet with a feed edge assembly showing our new design; FIG. 3 is a front view of a third embodiment of a label sheet with a feed edge assembly showing our new design; and, FIG. 4 is a front view of a fourth embodiment of a label sheet with a feed edge assembly showing our new design.

**1 Claim, 4 Drawing Sheets
